UNITED STATES PATENT OFFICE

110,923

DESIGN FOR A COMBINATION FOOD CHOPPER UNIT

Frank B. Gerard, New Haven, Conn., assignor to Sargent & Company, New Haven, Conn., a corporation of Connecticut

Application February 21, 1938, Serial No. 75,313

Term of patent 7 years

To all whom it may concern:

Be it known that I, Frank B. Gerard, a citizen of the United States, residing in New Haven, in the county of New Haven and State of Connecticut, have invented a new, original, and ornamental Design for a Combination Food Chopper Unit, of which the following is a specification, when taken in connection with the accompanying drawing:

Fig. 1 is a side elevation of a combination food chopper unit embodying my invention;

Fig. 2 is a top plan view; and

Fig. 3 is a front end view.

I claim:

The ornamental design for a combination food chopper unit, substantially as shown.

FRANK B. GERARD.
